UNITED STATES PATENT OFFICE.

EDWARD L. IVES, OF CHICAGO, ILLINOIS.

BLOWPIPE FOR BLAST-FURNACES.

1,362,702.

Specification of Letters Patent. Patented Dec. 21, 1920.

Application filed March 27, 1918. Serial No. 224,927.

To all whom it may concern:

Be it known that I, EDWARD L. IVES, a citizen of the United States, residing at Chicago, in the county of Cook and State of Illinois, 5 have invented certain new and useful Improvements in Blowpipes for Blast-Furnaces, of which the following is a specification.

My invention relates to means for securing heat insulation and protection for the 10 blow pipes of blast furnaces and has for its principal object the provision of heat insulated blow pipes for blast furnaces which will conserve the heat of the hot air blast 15 and prevent loss of heat by radiation as the hot air blast passes through the blow pipes into the furnace.

It will be understood that in the operation 20 of blast furnaces the hotter the air blast can be made, and conducted into the furnace the less fuel need be consumed within the furnace and a corresponding saving in fuel will be thus effected. Brick-work heat insulation has usually been provided 25 in the larger pipes but no effective means of insulating the blow pipes has heretofore been provided and when it is considered that each furnace has from eight to twelve blow pipes a very large surface is 30 exposed, thus causing a very great loss of heat from the air blast.

A further object of my invention is the provision of means whereby the blow pipes will be rendered more durable and will not 35 burn out so quickly in service thus necessitating frequent renewals.

A further object of my invention is the provision of insulating means which can be readily removed and renewed should occasion 40 require and which will be efficient and economical in operation, and which can be manufactured at low cost.

My invention will be further and better understood by reference to the accompanying drawings, and in which—

Figure 1 is a sectional view of the bottom of a blast furnace;

Fig. 2 is a sectional view of a blow pipe, and

Fig. 3 is a cross section on line 3—3 of Fig. 2.

Referring now specifically to the drawings and in which like reference characters refer to like parts throughout, 10 is the bosh wall 55 of the furnace, and 11 is the supporting column extending up to the mantle of the

furnace. The bustle pipe 12 carrying the hot blast extends circumferentially around the outside of the furnace wall and is held in position by means of a suitable support 60 13 secured to the top of the supporting column 11. Leading from the bustle pipe 12 is another pipe 14 commonly known as the "down leg" or "boot leg," suspended by means of a rod 15, or in any other suitable manner, and is connected to the blow pipe 16 by a ball and socket joint, the blow pipe extending through the furnace wall 10 and connecting at its inner end with the twyer 17, mounted within a twyer cooler 18. 70 The boot leg 14 is secured at its lower end by means of a rod 19 having a hinge connection with the blast furnace wall at its inner end and a coiled spring 20 on its outer end and passes through an opening in a downwardly 75 projecting lug 21 so that as the nut 22 on the outer end of the rod 19 is tightened, the pipe 14 will be drawn toward the furnace, and thus holding the blow pipe 16 securely in position. Fitting within the 80 blow pipe 16 I provide a cylindrical sleeve 23 preferably of asbestos or any other suitable heat resisting material which is held in position by contacting against an annular shoulder 24 on the inside inner end of the 85 blow pipe 16 and against the pipe 14 at its outer end when the blow pipe 16 is in position, slight allowance being made for expansion of the sleeve 23 under conditions of service. It will be understood that the cylindrical 90 sleeve 23 can be easily inserted into and removed from the blow pipe 16, and easily renewed when worn out in service. It will thus be seen that I provide a blow pipe 95 which in service is much more durable than the usual construction, and hence does not have to be renewed so frequently with the consequent loss of time and expense, and which will prevent the loss of heat from the air blast by radiation.

While I have described more or less precisely the details of construction which I employ, I do not wish to be understood as limiting myself thereto, as I contemplate changes in form and the proportions of parts and the substitution of equivalents as circumstances may suggest or render expedient without departing from the spirit or scope of my invention.

I claim:

1. In a blast furnace, a twyer, a blow pipe seated against and having an internal

shoulder in proximity to said twyer, a cylindrical insulating sleeve within said blow pipe and confined at its forward end by said shoulder, and a hot air pipe seating 5 against the rear end of the blow pipe and confining the sleeve therein.

2. In a blast furnace, a twyer, a blow pipe seated against and having an internal shoulder in proximity to said twyer, a cylindrical 10 removably fitting insulating sleeve within said blow pipe and confined at its forward end by said shoulder, and a hot air pipe seated against the rear end of the blow pipe and confining the sleeve therein.
- 15 3. In a blast furnace, a twyer, a blow pipe seated against and having an internal shoulder in proximity to said twyer, a cylindrical removably fitting asbestos sleeve within said

blow pipe and confined at its forward end by said shoulder and a hot air pipe seating 20 against the rear end of the blow pipe and confining the sleeve therein.

4. The combination of a blow pipe for blast furnaces and a cylindrical asbestos member removably positioned within said 25 blow pipe.

5. In combination, a blow pipe for blast furnaces, having an annular shoulder at its forward end and a removably cylindrical heat insulating member forming a lining for 30 said blow pipe, the said shoulder forming means for retaining the lining in proper position.

Signed at Chicago, State of Illinois, this 25th day of March, A. D. 1918.

EDWARD L. IVES.
